UNITED STATES PATENT OFFICE.

EDMUND S. DICKEY, OF BALTIMORE, MARYLAND, ASSIGNOR TO AMERICAN METER COMPANY, INC., OF NEW YORK, N. Y., A CORPORATION OF DELAWARE.

METHOD OF MAKING BELLOWS MATERIAL FOR GAS-METER DIAPHRAGMS.

Application filed August 30, 1922. Serial No. 585,266.

This invention relates to improvements in bellows material for gas meter diaphragms, and method of making the same.

Diaphragms for dry type gas meters for domestic purposes have been invariably made of leather, and in order to get a leather suitable for this, skins of various kinds have been tried, which have been variously treated to make them impervious to gas, and finally, whole sheep skin or hide of the best selected stock, on account of the peculiar physical characteristics of this hide, such as pliability, strength, and absorbent qualities that make it receptive of the oils and other substances with which the leather is treated, before going into the meter, have been universally adopted for making the bellows portion of diaphragms.

This material, however, has certain disadvantages, especially on account of the action of oil and water gases, and various mixed gases, and natural gases, which have now taken the place of gas that for many years has been generally made from coal. The condensates and agencies of the gases very quickly attack these artificial oils used in the treatment of the leather, destroying, absorbing, or otherwise eliminating them, for no matter how thoroughly the leather now commonly used is treated, on both sides, necessarily from the outside, there is always an intermediate area into which the oils and greases do not penetrate, and furthermore, lack of uniformity in the thickness or character of the leather, or the presence of "spots", makes it impossible to produce a meter bellows of uniformity, both as to character of the material and its action in operation. The elimination of the artificial oils by the gas condensates causes rotting, drying out, bleaching, shrinking, and otherwise seriously affects the bellows material, with the result that the length of service and accuracy of the meter is curtailed.

The object of this invention is to overcome the disadvantages incident to the materials of which diaphragms have heretofore been made, and to greatly cheapen the same. In order to do this, I provide a diaphragm constructed of plates or layers of textile material, or of split leather hides, but preferably of suitable woven fabric, constructed in a novel manner, and treated in a novel manner, and which in its final condition, has been found by experiment to be

absolutely gastight under all of the conditions in which diaphragms of this character are used.

I propose primarily, and as representing the best embodiment of my invention, to take layers of textile material and unite them in a strip by suitable stitching so that the layers will be joined together, or united for uniform simultaneous movement in all parts, as well as to provide between the layers pockets for receiving and holding a preservative, sealing and filling substance, or a substance which is worked into and fills, seals and lubricates the interstices or pores of the material, and finally coat the strip on both the outer sides with a substance that combines with the substance between the layers, for further effective sealing and lubrication.

I further propose to provide a line, or lines, of stitching that not only serves to unite or aid in uniting the layers of fabric together, but in the final diaphragm, serves an additional advantageous purpose, this purpose being to stiffen the arc of the bellows portion of the diaphragm to insure uniform movement in the collapsing operation of the diaphragm.

Secondarily, and as representing a modification of the invention, made practicable by the added possibilities and facilities of treatment of the material, which result from the layer construction, I may take plates of split leather, which plates may be entirely of either the grain face or of the flesher side of the skin, and accordingly much cheaper than the whole skin.

Furthermore, I may previously shape the strip, when made of fabric or textile material, so that after the filling and sealing material has been introduced between the layers, and worked into the pores or interstices of the material, the strip may be readily attached to the diaphragm rings without the usual pucker incident to adjusting a skin strip.

Following the use of textile material, is another feature deserving of consideration. The stitching together of sections of leather diaphragms now commonly used, as shown in Fig. 14, is a tedious operation requiring great care to prevent the stitches from being carried all the way through the material, for if they are carried through the leather, complete punctures or perforations are made

that give trouble later from seam leaks, no matter how thoroughly the leather is treated or saturated with the artificial oils usually employed; whereas, incident to stitching entirely through layers of textile fabric, there are none of these disadvantages, since the character of the stitching is the same as that of the material which surrounds it, and if anything, augmenting the filling possibilities rather than detracting from them.

In the drawings herewith serving to illustrate the method:

Fig. 1 is a plan view of a strip of fabric, before stitched or treated.

Fig. 2 is a similar view showing the manner of stitching.

Fig. 3 is a sectional perspective view showing the strip stitched, and the pockets thereof filled with the sealing and lubricating substance, before it has been worked into the interstices of the fabric.

Fig. 4 is a similar view showing the layers of the strip pressed together, and intended to show the condition of the fabric after the filling, sealing and lubricating substance has been absorbed into the fabric.

Fig. 5 is a plan view showing the manner of cutting the strip preparatory to forming into a band suitable for attachment to the diaphragm rings.

Fig. 6 is a perspective view of a band of filled, sealed and lubricated material ready to be placed upon the diaphragm rings.

Fig. 7 is an edge view of a diaphragm construction in accordance with my invention, before final treatment.

Fig. 8 is an enlarged broken sectional view of a portion of a diaphragm, also before the final treatment.

Fig. 9 is a similar sectional view of a portion of the diaphragm in its final condition.

Fig. 10 is a perspective sectional view of a part of the bellows portion of the diaphragm showing the same shaped previous to attachment to the diaphragm rings.

Fig. 11 is a perspective sectional view showing the strip of fabric made in tubular form.

Fig. 12 is a group of fragments of the textile strip in plan, showing different manners of stitching the layers together.

Fig. 13 is a broken detail perspective view of part of a strip, the layers of which are leather.

Fig. 14 is a detail cross sectional view showing the usual manner of stitching together leather sections of bellows material, the thickness of the sections being greatly exaggerated.

Referring to the drawings, the numeral 1 designates a strip formed of two layers or plates 2 and 3 of textile fabric, preferably closely woven fabric, and I have found by experiment, that the fabric known on the

market as middy twill muslin is suitable for my purpose.

The fabric is cut of a width which when folded once upon itself will form a strip of the desired width, and it will be understood at the outset, that the widths will vary as well as the lengths of the strips according to the size of the diaphragm. After folding the fabric to form the layers or plates 2 and 3, I then stitch the strips longitudinally adjacent to its longitudinal edges, as indicated at 4, thus providing longitudinal edges 5 outside the stitches, which edges 5 are, in applying the substitute to the metallic diaphragm rings, crimped into the grooves of 80 the rings, as shown in Figures 7, 8 and 9, and secured therein by cords *a* in the usual manner.

The strip is further united centrally and longitudinally preferably by a row of stitching 6. This stitching is for several important purposes. Primarily, it divides the strip into two similar longitudinal or lengthwise pockets 7, into which for the entire length of the strip is introduced a preservative and lubricating filler 8, preferably of powdered graphite of the proper consistency, and in the final condition of the strip, the central stitching 6 forms a stiffener for the arc of the bellows portion insuring the proper action of the material in the expanding and collapsing operation of the bellows. Furthermore, the stitching forms definite pockets which contain and hold and keep evenly distributed the graphite filling.

The graphite is worked into the interstices of the fabric until the major portion thereof has been completely absorbed by the fabric bringing the strip to substantially the condition shown in Fig. 4, and it will be understood that throughout all of the views, and especially 3, 4 and 6, the thickness of the layers of fabric is very greatly exaggerated.

After the graphite is worked thoroughly into the interstices of the fabric, the strips are cut into proper lengths, as indicated in Fig. 5, and then as shown in Fig. 6, the strip is united at its ends by two rows of stitches 9. The band is then placed upon the grooved flanges 10 and 11 of the metallic diaphragm rings 12 and 13, and secured there by the cords *a*, as before indicated, there being used in the attachment the usual materials, such as shellac, with which the cords are coated to make an absolutely gas-tight joint.

After the strip is secured to the rings, I treat the strip both inside and out, as indicated at *b*, with a coating of a mixture of dry graphite and suitable grease, such as petroleum jelly, which penetrates the fabric and unites with the filler which was introduced between the layers, and which was absorbed between the interstices of the lay-

ers, thus producing a strip or bellows of substantially homogeneous character, which character the illustration in Fig. 9 is intended to show.

5 The formation of the pockets made by the central stitching 6 I have found facilitate the uniform working in of the filler, as well as, as before stated, providing in the final condition of the bellows, a central stiffening portion which insures the proper action of the material in the expanding and collapsing movement of the bellows which it must constantly endure when gas is passing through the meter and being measured.

10 15 I have found that the use of powdered graphite of the proper grade, serves admirably the purpose of completely filling and sealing the interstices of the fabric, and at the same time so lubricates the closely associated threads of the fabric as to reduce to a minimum the possibilities for gas absorption of the artificial lubricants of the bellows material, thereby maintaining the continued flexibility of the diaphragm.

20 25 As before stated, after the graphite filled strip is placed upon the diaphragm rings, the strip is coated both inside and out, as indicated at 7, with a mixture of powdered graphite of the proper grade and consistency, and grease, such as petroleum jelly, this coating being absorbed and uniting with the graphite introduced between the layers of fabric.

30 35 There is illustrated in the main figures, a strip formed of two layers, the layers being formed by folding the fabric upon itself, and being stitched, as described. Further attention is called to the Figures 10, 11 and 12, which will be considered as modifications 40 of the structure described, and I do not desire to be understood as limiting myself to the number of layers of material employed, or the manner of stitching them together, or uniting them, and as shown in Fig. 11, the 45 strip may be woven in true tubular form, and suitably stitched, but preferably, by the marginal lines of stitching 14, and central line 15, the result being, as in the construction first described, the provision of 50 pockets 16, corresponding in every essential way with the pockets 7 for the reception of the filler.

55 As shown in Fig. 12, additional stitches may be provided, such as the vertical rows 17, and longitudinal rows 18, which form rectangular pockets 19, in the fragment 20, and where stitches of this form are used it is desirable to run an additional row of 60 stitches 21 centrally of the strip so that in the completed diaphragm, stiffening means will be provided for the central portion or arc of the bellows. In the fragment 22, oblique additional stitches 23 are made in two directions, thus forming substantially 65 rectangular pockets 24, and in the fragment

25, additional oblique stitches 26 are made in one direction, forming the elongated rhomboidal pockets 27. These various lines of stitching serve, as before suggested, to unite the layers of fabric, and at the same time provide comparatively diminutive pockets for stabilizing the filling material that has been introduced between the layers and thoroughly worked into the interstices of the fabric, before the additional stitches 70 75 are made.

Previous to placing the strip upon the diaphragm rings, I may shape it as shown in Fig. 10, wherein there is formed a central dome portion 28, which merges into laterally extending marginal edges 29, which seat accurately and smoothly in the grooves in the diaphragm rings, in which grooves they are held in the ordinary way. This preshaping eliminates the wrinkling 80 and puckering of the bellows adjacent the rings, which is invariably incident to the use of leather.

85 I have found that for the outside treatment of the bellows material, a combination of dry powdered graphite and petroleum jelly, mixed in about the proportions of three ounces of suitable grade graphite, with two pounds of petroleum jelly, produces a grease that gives admirable results, and this mixture is preferably applied to the fabric while hot, and approximately at a temperature of 120° Fahrenheit.

90 I do not limit myself to the kind of grease used for this outside treatment, but as just suggested, I have found that the combination of petroleum jelly and graphite makes an admirable mixture, nor do I desire to limit myself in any way to the manner of stitching the layers together, for obviously, the stitches may be run in various directions, and made to cross each other at varying intervals, or they may be straight, or undulatory as may be desired, for in all events, they are intended for the purpose 100 of uniting the layers of fabric so that the layers will move together, and for forming pockets for stabilizing the filling material that has been introduced between the layers.

105 110 I desire it understood that by the use of the term "tubular", I mean that the strip in its final condition is in tubular form, and that it does not matter whether it is made tubular by folding one layer upon the other, and stitching along one marginal edge, or by stitching upon two marginal edges, as shown in Fig. 2, or by the weaving in tubular form, as shown in the modification, Fig. 11, or rendered tubular by uniting the two marginal edges of the layers upon the diaphragm rings.

115 120 In referring to the modification illustrated in Fig. 13, the numeral 30 designates two layers of leather, which as hereinbefore indicated, may either be the grain face or 125 130

the flesher side of the leather, or a leather of cheap, inferior grade, which however, by reason of the construction of the strip with the possibilities and facilities of treatment which have heretofore been indicated, produces a bellows material of very acceptable quality, which possesses advantages over the material heretofore used.

Merely to show the present method of stitching together sections of leather which go to make up the ordinary leather diaphragm, I have added Fig. 14. Referring to this figure, the numerals 31 and 32 designate two leather sections, whose ends are overlapped as indicated at 33, the sections being stitched together by stitches 34, which it will be observed do not extend entirely through the sections at points exposed to gas action.

20 Claims.

1. That process for forming and treating bellows material for dry type gas meter diaphragms and the like, which consists in providing a tubular member of flexible material, and impregnating said member from the inside thereof with a non-setting comminuted substance to completely fill and seal the pores or interstices of the material.

2. That process for forming and treating bellows material for dry type gas meter diaphragms and the like, which consists in providing a tubular flexible member of suitable material, impregnating said member, from the inside with a powdered lubricant to completely fill and seal the pores or interstices of the material.

3. That process for forming and treating bellows material for dry type gas meter diaphragms and the like, which consists in providing a tubular flexible member of suitable material, and impregnating said member from the inside thereof with dry powdered graphite to completely fill and seal the interstices or pores of the material.

4. That process for forming and treating bellows material for dry type gas meter diaphragms and the like, which consists in providing a tubular flexible member of suitable material, and impregnating said member from the inside thereof with a non-setting comminuted substance to fill and seal the pores or interstices of the material, and in finally coating both sides of the member with a substance that permeates said material, and combines with the first mentioned impregnating material, to completely fill and seal the pores or interstices of the material.

5. That process for forming and treating bellows material for dry type gas meter diaphragms or the like, which consists in providing a tubular member of flexible material, impregnating the member from the inside with dry graphite, and on the out-

side with a grease formed of a mixture of oil and dry graphite, to completely fill and seal the pores of the material.

6. That process for forming and treating bellows material for dry type gas meter 70 diaphragms and the like, which consists in providing a tubular flexible member of suitable material, and strengthening longitudinally said member to provide a definite stiffening arc, and impregnating said member 75 from the inside with a substance for filling and sealing the pores or interstices of the material.

7. That process for forming and treating bellows material for dry type gas meter 80 diaphragms and the like, which consists in providing a tubular flexible member of suitable material, strengthening said tubular member longitudinally to provide definite and permanent stiffening arc, impregnating 85 said member from the inside with powdered graphite, and on the outside with a grease formed of a mixture of powdered graphite and oil, to completely fill and seal the interstices or pores of the material. 90

8. That process for forming and treating bellows material for dry type gas meter diaphragms and the like, which consists in providing a flexible strip of textile material in layers, and impregnating the strip from 95 between the layers with a non-setting comminuted substance to completely fill and seal the interstices or pores of the material.

9. That process for forming and treating bellows material for dry type gas meter 100 diaphragms and the like, which consists in providing a flexible strip of textile material, formed in layers, impregnating the strip from between the layers with powdered graphite to completely fill and seal the interstices or pores of the material, and lubricate 105 the closely associated parts and insure the continued flexibility of the material.

10. That process for forming and treating bellows material for dry type gas meter 110 diaphragms and the like, which consists in providing a tubular flexible member of textile material, and impregnating the member from the inside with a substance that fills and seals the pores of the fabric, and finally 115 applying to the outside of the member a non-setting comminuted substance in a heated condition, which permeates the textile material and combines with the first mentioned impregnating material for the purpose set 120 forth.

11. That process for forming and treating bellows material for dry type gas meter diaphragms and the like, which consists in providing a tubular flexible member of textile material, impregnating the member from the inside with powdered graphite, and finally applying to the outer sides of said member, a mineral grease composed of powdered graphite and petroleum jelly. 125 130

12. That process for forming and treating bellows material for dry type gas meter diaphragms and the like, which consists in providing a flexible strip in layers, and impregnating the strip from between the layers with a substance to completely fill and seal the pores or interstices of the material, and providing pockets between the layers to stabilize the impregnating material. 50
13. That process for forming and treating bellows material, for dry type gas meter diaphragms and the like, which consists in providing a flexible strip in layers, and impregnating the strip from between the layers with a substance to completely fill and seal the pores or interstices of the material, and providing pockets by stitching between the layers, which unite the layers and stabilize the impregnating material. 55
14. That process for forming and treating bellows material for dry type gas meter diaphragms and the like, which consists in providing a flexible strip in layers, and impregnating the strip from between the layers with a substance to completely fill and seal the pores or interstices of the material, and providing pockets between the layers to stabilize the impregnating material; and finally applying to the outer sides of the layers, a substance which permeates the material and combines with the first mentioned impregnating material. 60
15. That process for forming and treating bellows material for dry type gas meter diaphragms and the like, which consists in providing a tubular member of flexible textile material, and stitching layers of flexible material with stitches that extend entirely through the material for the purposes set forth, and impregnating said member with a substance to completely fill and seal the pores or interstices of the material. 65
16. That process for forming and treating bellows material for dry type gas meter diaphragms and the like, which consists in providing a strip of textile material formed in layers, impregnating said member from the inside with a substance to completely fill and seal the pores or interstices of the material. 70
17. That process for forming bellows material, which consists in providing a flexible strip in layers, impregnating the strip from between the layers with a substance to completely fill and seal the pores or interstices of the material, and stabilizing the impregnating material between the layers. 75
18. That process for forming and treating bellows material for dry type gas meter diaphragms and the like, which consists in providing a tubular flexible member of suitable material, impregnating said member from the inside thereof with a non-setting comminuted substance to fill and seal the pores or interstices of the material, coating both sides of the member with a substance that permeates said material and combines with the first mentioned impregnating substance to completely fill and seal the pores, or interstices of the material, the last mentioned substance being applied to the material while hot. 80
19. That process for forming and treating bellows material for dry type gas meter diaphragms and the like, which consists in providing a tubular flexible member of suitable material, impregnating said member from the inside thereof with a non-setting comminuted substance to fill and seal the pores, or interstices of the material, coating both sides of the member with a substance that permeates said material and combines with the first mentioned impregnating substance to completely fill and seal the pores, or interstices of the material at a temperature of approximately 120° F. 85
- In testimony whereof I affix my signature.
- EDMUND S. DICKEY.
